US00D872965S

(12) **United States Design Patent** (10) **Patent No.:** **US D872,965 S**
(45) **Date of Patent:** **** Jan. 14, 2020**

(54) **PALLET TRUCK**

(71) Applicant: **Big Lift, LLC**, Lombard, IL (US)

(72) Inventors: **Liu Yuanwei**, Hangzhou (CN); **Chen Jianwei**, Hangzhou (CN); **Meng Feiquan**, Hangzhou (CN); **Kang Jianming**, Hangzhou (CN); **Yu Jiandong**, Hangzhou (CN)

(73) Assignee: **Zhejiang E-P Equipment Co., Ltd.** (CN)

(**) Term: **15 Years**

(21) Appl. No.: **29/644,424**

(22) Filed: **Apr. 17, 2018**

(51) LOC (12) Cl. **12-05**

(52) U.S. Cl.

USPC **D34/34**

(58) **Field of Classification Search**

USPC **D34/28, 34**

(57) **CLAIM**

We claim the ornamental design for a pallet truck, as shown and described.

DESCRIPTION

FIG. 1 is a left rear perspective view of a pallet truck according to our new design;

FIG. 2 is a right rear perspective view of the embodiment in FIG. 1;

FIG. 3 is a left front perspective view of the embodiment in FIG. 1;

FIG. 4 is a right front perspective view of the embodiment in FIG. 1;

FIG. 5 is a rear perspective view of the embodiment in FIG. 1;

FIG. 6 is a front elevational view of the embodiment in FIG. 1;

FIG. 7 is a rear elevational view of the embodiment in FIG. 1;

FIG. 8 is a left side elevational view of the embodiment in FIG. 1;

FIG. 9 is a right side elevational view of the embodiment in FIG. 1;

FIG. 10 is a top plan view of the embodiment in FIG. 1; and, FIG. 11 is a bottom plan view of the embodiment in FIG. 1. The broken lines shown in the figures are included for the purpose of illustrating portions of the pallet truck and form no part of the claimed design.
